POCKET SPRAY DEVICE

Samuel L. Margolies, Brooklyn, N. Y.

Application September 9, 1940, Serial No. 355,920

4 Claims. (Cl. 299—89)

This invention relates to pocket spray devices, and more particularly relates to pocket devices which may, with slight adjustment of parts, operate as sprays or atomizers.

The invention is directed to a particular construction of parts which permit easy and simple manufacture, and includes the feature that no leakage can occur in the device when it is not in operating position.

Pocket sprays and atomizers have previously been proposed, but for the most part they possess the difficulty that leakage is bound to occur, as they are carried by the individual user and for this reason they have been found to lack practical application. Many such devices have the further disadvantage that no provision is made to supply air to the liquid container to replace removed liquid, so that if such devices operate at all their operation is uncertain and irregular. Furthermore such devices are either sprays or atomizers and one cannot be modified to perform the functions of the other, which is a disadvantage when various types of liquids are to be provided for.

It is an object of this invention to provide a pocket spray device which may, by adjustment of very simple parts, be made into an atomizer or a spray, as the manufacturer may desire, thus providing spraying devices for liquids of a wide range of specific gravity, and which, in either case, will be a complete leak proof combination of parts from which liquid can only be obtained as is desired by the user.

It is an object of the invention to provide a spray device in which ample provision is made to replace removed liquid in the liquid container with air, without causing any undesired leakage in the device, thus insuring continuous smooth operation.

A further object of the invention is to produce such a spray device with very small over-all dimensions, and which may be carried in a lady's pocketbook or a gentleman's pocket.

Further objects and advantages will appear from the following description and the appended drawing in which

Figure 1 is a vertical section of device embodying the construction of the invention;

Figure 2 is a section similar to Fig. 1, showing a sprayer construction having a modified container;

Figure 3 is a section similar to Fig. 1, showing the parts adjusted for atomizing;

Figure 4 is a detailed showing of the spray construction of Fig. 1; and

Figure 5 is a section similar to Fig. 1, showing a modified form of atomizer.

Referring particularly to Fig. 1 a liquid container is shown as a glass bottle 10. The container may be of any convenient transparent material or may be of opaque material such as plastic or metal. The bottle 10 is provided with a threaded metal collar 11 about its neck which permits it to be easily secured to the other parts of the construction. Located within the liquid container 10 is the cylindrical air chamber 12 which contains a piston 13 provided with port 16 and secured to a plunger 14, the spring 15 tending to push the piston and plunger upwardly when the device is operated. The port 16 may take any convenient form and is intended only to provide for introduction of air into the space below the piston on its up stroke, thus eliminating the possibility of liquid being drawn into the cylinder.

10 The top portion of the device is provided with a collar member 17 having an interiorly threaded portion 18 which cooperates with the collar 11 of the bottle 10. Member 17 extends inwardly at 22 and has the downward step 19 and terminates on its inner side with the threaded cylindrical portion 20. The gasket 21 insures that no leakage will occur at the top of the bottle 10.

20 The inverted cup-shaped member 25 is provided with threads 26 on its outer side which cooperate with the threaded portion 20 of the collar 17. A shoulder 27 is provided on the member 25 directly below the threads 26 and limits the downward movement of the collar member 17. The cup-shaped member 25 has a top horizontal platform 28 in which the air vent 29 is provided. The platform 28 also has the threaded hole 30 which in this embodiment contains the plug 31. On one side of the member 25 is provided the threaded hole 32.

25 The tube 34 from air chamber 12 has descending portion 39, hole 35 near the bottom of the liquid container, and ascending portion 36 which turns outwardly at 37 into spraying zone 38 which may take any convenient form which will break up a stream of liquid and air into a spray and is here shown as the freely revolving screw 38.

30 The upwardly ascending portion 36 of the tube 34 may if desired be provided with an auxiliary air hole 44.

35 The top of the plunger is provided with cap 40 having the downwardly descending interiorly threaded cylindrical portion 41 and gasket 42. In normal position, when the device is not in operation, the cap 40 will be in threaded engagement with the threads 26 on the cup-shaped

member 25 and will fit into the step portion 19, the gasket 42 fitting snugly over the platform 28 so that the cap forms an effective seal against leakage. The gasket 23 may also be provided in the step 19 further to seal the cap 40.

To operate the device the cap 40 is unscrewed and the piston is operated up and down forcing air under compression through tube 34 which air displaces liquid at 35. The mixture of air and liquid is broken up at 38 and a fine spray is ejected through the hole 32.

In some cases it is particularly desirable, due to the nature of the liquid material to be carried, to use glass or other inert material for the liquid container. In such cases it may also be desirable to have a more durable outside container of metal or the like. In Fig. 2 such a construction is shown, using however the same parts to mount the liquid container and outside shell. Thus the collar member 17, cup-shaped member 25, and cap 40 are precisely the same as in the construction of Fig. 1. The interior liquid container 50 of glass or other convenient inert material has exteriorly threaded neck 51 which is screwed into the interiorly threaded portion of the inverted cup-shaped member 25. The gasket 52 is provided to prevent leakage from the top of the interior bottle 50.

In Figure 3 a construction is shown which adapts the parts used in Figures 1 and 2 for use as an atomizer. The outside container may be as in Figs. 1 or 2, or may, as shown, be of metal or plastic, and may, if desired, have the bottom cap 60 to facilitate refilling. In this construction a tube 64, downwardly extending from the air chamber 65, is provided with no hole as described in the first two embodiments. A second tube 66 ascends from below the liquid level to slightly above the platform 28. Tube 64 terminates above platform 28 and is formed to point over the top of the tube 66 so that emission of air at high velocity from the tube 64 will cause liquid to be drawn up the tube 66 and to be atomized in the direction which the tube 64 is pointing. It is seen that in this embodiment the hole 32 is plugged. The tube 66 preferably terminates at its lower end in substantially horizontal portion 67 and upwardly turned portion 68 which will operate to insure that no leakage occurs through this tube. The tube 64 is provided with the air vent 69 which supplies air to replace the liquid removed through tube 66, thus insuring regular and steady flow of atomized liquid.

Comparing now the three types of spray devices shown in Figs. 1, 2, and 3, it will be seen that many parts may be used commonly for all three types and the expense of manufacturing will be considerably below that required to manufacture an ordinary spray and an ordinary atomizer. The outside container may, as stated, be interchangeably used either as a guard for a bottle or as the liquid container itself. The piston and plunger construction obviously may be used interchangeably, as may the collar 17, the cup-shaped member 25 and the cap 40. It is further possible to adjust an atomizer into a spray or vice versa should the user so desire. This may be accomplished in the case of a spray by replacing the tube 34 which has the hole 35 with a tube such as 64 having no hole, and by removing the plug 31 from the hole 30, placing it in the hole 32, and providing a further hole 69 adjacent the hole 30 for tube 64.

In Figure 5 is shown a slightly modified con-

struction of atomizer including the liquid container 70 which, it will be noted, is merely a tube having a slightly undercut portion at its lower end to accommodate the bottom cap 71 and having an interiorly threaded zone 72 at its top. The bottom cap may also be formed integrally with the tube 70. An inverted cup 73 is utilized in this construction to close the top of the liquid container, said closure member having a threaded 10 cylindrical portion 75 which engages the thread 72, an annular shoulder 75 preferably having gasket 76, a cylindrical portion of less diameter 77, and a top platform 78. Cap member 79 is secured to the plunger and has an exteriorly 15 threaded portion 80 which cooperates with the threaded portion 72, the lower parts of the cap 79 fitting into the groove formed by threaded portion 72, the annular platform 75 and the cylindrical portion 77, and are sealed against 20 leakage by the gasket 76. The atomizer portion of this construction is similar to that described in connection with Fig. 3. Considerable economies of manufacture may be effected in the 25 fashioning and assembling of these simple parts, particularly since the tube and cap member 73 are so easily constructed.

While I have illustrated and described in detail certain preferred forms of my invention, it is to be understood that changes may be made 30 therein and the invention embodied in other structures. I do not, therefore, desire to limit myself to the specific constructions illustrated, but intend to cover my invention broadly in whatever form its principle may be utilized.

35 I claim:

1. A pocket device for producing a liquid spray including a liquid container comprising a tube interiorly threaded at the top thereof and closed at the bottom, an air chamber in 40 said container having a piston and plunger, a cap over the top of said tube comprising an exteriorly threaded cylindrical portion which cooperates with said interiorly threaded top of said tube, an inwardly extending portion forming 45 an annular shelf, an upwardly extending cylindrical portion and a horizontal portion through which extends said plunger, and means for forcing a fine spray of liquid from said container by operation of said piston, said means 50 extending through said horizontal portion of said cap.

2. A device as claimed in claim 1 in which a closure member is secured to the top of said plunger, having a horizontal top and a cylindrical 55 downwardly depending, exteriorly threaded side wall, said threaded portion of said closure member cooperating with some of said threads on said tube and sealing means on the under side of said closure member adapted to fit over and seal the delivery end of the spray 60 ejecting means.

3. A pocket device for producing a fine spray of liquid including a liquid container, a tube within said container, said container and said 65 tube being held in permanent relation to each other by a cup-shaped member inverted over and secured to an end of said container and supporting said tube, an atomizing element extending through said member, means to conduct liquid from the container to the atomizing element, a piston in said tube having a plunger 70 extending through said member, means to bring a blast of air to said atomizing element for atomization of liquid on operation of said plunger, a cap secured to the upper end of said 75

plunger having a downwardly depending flange about its periphery, said flange being threaded on one side thereof, and threading into an annular groove formed in the top of said device, at least a portion of said groove being formed in said cup-shaped member and said cap covering the exposed portion of said atomizing elements when closed.

4. A pocket atomizer including a liquid container having an interiorly threaded upper portion, closure means for said container cooperating with a part of said interiorly threaded portion, an atomizing element extending through

said closure means, a cylinder depending from said closure means into said container, a piston in said cylinder and a plunger secured to said piston and extending through said closure means, means to supply air under pressure to said atomizing element from said cylinder and means to secure said atomizing elements from leakage of liquid when not in use, said means including a cap mounted upon the upper end of said plunger and cooperating with a part of said threaded portion of said tube.

SAMUEL L. MARGOLIES.
